COMBINED SCORE PAD AND GAME SCORE INDICATOR

Roland F. Wilson, Minneapolis, Minn.

Application May 5, 1932. Serial No. 609,541

3 Claims. (Cl. 235—90)

This invention relates to a combined score pad and game score indicator for contract auction bridge.

An object of the invention is the provision of a combined score pad and indicator for the game of contract auction bridge which will have visible indicators to disclose at any stage of the game a game score of a partnership and also to show whether or not either side is vulnerable.

10 Another object of the invention is the provision of a combined score pad and game score indicator for contract auction bridge in which the score may be kept by a scorekeeper during the game with manually rotatable discs mounted upon the back of the score pad and provided with numbers for representing the game score of a partnership at any stage during the game with sight windows in the back for exposing individual numbers on the discs in connection with pivotally mounted arms which are adapted to be moved in a conspicuous manner adjacent the exposed number for indicating whether or not either side or partnership is vulnerable.

15

20 A further object of the invention is the provision of a score pad having a rigid back formed of several sheets of heavy material spaced from each other with discs rotatably mounted on one of the members and located in the space between said members, the discs being provided with numbers which may be exposed through a sight opening to indicate the game score at any stage during a game of contract auction bridge with indicators movable to an exposed position adjacent the exposed number for indicating whether or 25 a side or partnership is vulnerable.

30 This invention will be best understood from a consideration of the following detailed description, in view of the accompanying drawings forming a part of the specification; nevertheless, it is to be understood that the invention is not confined to the disclosure, being susceptible of such changes and modifications which shall define no material departure from the salient features of the invention as expressed in the appended claims.

35 In the drawings:

Figure 1 is a plan view of a combined score pad and game score indicator constructed in accordance with the principles of my invention.

40 Figure 2 is a similar view showing the cover raised and showing a score card.

45 Figure 3 is a vertical section taken along the line 3—3 of Figure 2.

50 Figure 4 is a horizontal section taken along the line 4—4 of Figure 2,

Figure 5 is a plan view of a disc provided with numerals for indicating the score of a partnership.

Figure 6 is a plan view of a modified form of a score pad and game score indicator in folded 60 position,

Figure 7 is a plan view in an open position of the score pad and game score indicator,

Figure 8 is a vertical section taken along the line 8—8 of Figure 7, and

Figure 9 is a view in perspective of an indicator.

In order to intelligently bid a hand of contract bridge a bidder must know how the game stands before proceeding. In other words, the bidder must know how many points each side has made up to that stage in the game and he must also know whether or not either side or partnership is vulnerable. Questions are continually asked during the course of the game of the person keeping the score as to how the game stands and whether either side is vulnerable.

10 In order to overcome this difficulty numerals 10 and 11 located respectively upon discs adjacent the periphery of the discs 12 and 13 are displayed through sight openings at all times so that any of the players may determine at a glance what the game score is.

15 A rigid back 14 is provided upon which the discs 12 and 13 are rotatably mounted by means of pins 15. These pins are provided with a head 16 which engages the outer surface of the back 14 with the inner ends, as shown at 17, engaging the outer surface of an inturned portion 18 of a cover 19 for a pad 20.

20 The portion 18 of the cover 19 rests upon a second back member 21 which is secured to the member 14 by means of fasteners 22. The upper edge of the member 21 terminates adjacent the upper edge of the member 14 so that said members are of substantially the same length and width.

25 The pad 20 consists of a number of sheets of paper connected together, as shown at 25, adjacent their upper edges. These sheets of paper 30 forming the pad are provided with vertical lines 26 and 27 forming longitudinal columns with indicia at 28 and 29 representing several partnerships of the game. A line 30 extends transversely and at right angles to the lines 26 and 27 and is disposed approximately midway of each sheet. The columns above the line 30 are adapted to receive the score relating to the honors while portions of the columns below the line 30 are adapted to contain the game score of the several parts.

nerships. This game score is also visibly indicated by the numerals shown at 10 and 11 on the discs 12 and 13.

The side edges of the members 14 and 21 of the back of the pad are cut away, as shown at 31 and 32 to permit portions of the discs 12 and 13 to be exposed for manipulation.

As shown at 33 and 34 the upper portion 35 of the member 21 which extends beyond the upper edge 23 of the pad 20 is cut away to provide sight openings through which the numerals on the discs 12 and 13 are exposed to view.

Indicia, as shown at 36 and 37, are placed upon the upper exposed edge 35 of the member 21 to indicate the different partnerships of the game and thus associating the partnership with one of the discs 12 or 13.

Arms 40 and 41 are pivotally mounted either on the pins 15 or they may have a separate mounting eccentric with respect to the pins 15. These arms project beyond the outer edges of the discs 12 and 13 and beyond the upper extreme edge 42 of the members 14 and 21. Indicia are placed upon the exposed portion of the arms 40 and 41 with the abbreviation "Vul." and a flag with the abbreviation representing the word "vulnerable". These arms may be exposed directly above the numbers exposed in the windows 33 and 34 or the arms may be moved to a position as shown in Fig. 1 at 40 where the arm is substantially housed between the members 14 and 21 of the back.

The inner face of the cover, as shown at 43, may be provided with indicia giving briefly the rules of the bridge game and with the numbers representing the bids for the various cards.

As shown more particularly in Figs. 1 and 2, the numeral 60 appears in the column represented by the word "They" and indicating the game score of one partnership. The numeral 70 is shown applied to the first column under the designation "We", representing the other partnership. These numerals have been placed after careful consideration in these columns by the scorekeeper and this score is ordinarily not exposed to view so that it would necessitate the bidder at times to inquire as to the score and whether or not a side is vulnerable. In order to overcome this difficulty, the exposure of the game score, as shown in Fig. 1 by the numerals 60 and 70, as indicated at 10 and 11, will eliminate this difficulty since any of the bidders may readily inspect the visible indicator and determine for himself the game score.

When a side or partnership is "vulnerable" the scorekeeper places the arm 41 in the position shown in Fig. 1 and extending outwardly beneath the numeral 60. The arm 40 representing the other side is moved on its pivot to the position shown at 40 so that the bidder or a player may determine readily by inspection which side is vulnerable. The outwardly projecting arm 41 represents that the partnership "They" is vulnerable while the substantially hidden arm 40 may be moved to its exposed position beneath the numeral 70 when the partnership, indicated by "We" is vulnerable.

Referring more particularly to the construction shown in Figs. 6 to 9, inclusive, it will be seen that a relatively stiff sheet of paper forms the front and back covers of the score pad, as shown at 80. This strip of material is folded as shown at 81 adjacent the inner end of a pad 82 which is secured at 83 to the strip or sheet 80. The pad

has the usual lines and indicia for the keeping a score.

One end of the strip or sheet 80 is folded upon itself as shown at 84 with the free end 85 terminating in spaced relation with the inner end of the pad 82. The portions 86 and 87 of the backing or covering 80 are spaced apart and held together by means of fasteners 88 and 89 of well known type.

A disc 90 is rotatably mounted on the fastener 89 and is located between the members 86 and 87. The portion of the disc adjacent the periphery is provided with a series of numerals, as shown at 91, which are adapted to be exposed before a sight opening 92 formed in the member 87.

The sides of the members 87 and 86, as shown at 93, are cut away to permit the operator to engage the periphery 94 of the disc 90 for rotating the disc and for displaying consecutive numerals 91 before the sight opening or window 92.

A lever 95 is also pivoted on the fastener 89 and is provided with a right angular extension or arm 96 having a designation in the form of a flag, as shown at 93, adapted to be displayed through the window 92 inwardly of a numeral 91. When this flag 97 is exposed through the window 92 it will indicate that the side represented by the numeral 98 is "vulnerable". The lever 95 is provided with a reinforcement 99 and a portion of 105 the arm where the reinforcement has been applied projects through a slotted portion formed between the curved slits 100 and 101. The space 102 not only serves as a guide for the lever 95, but provides for the exposure of the reinforced 110 portion 99 while permitting the operator to grasp this portion and move it from opposite ends of the slotted portion 102. The slits 100 and 101 are located in the member 87.

A second disc 110 is rotatably mounted on the 115 fastener 88 as is a lever 111. The disc 110 is provided with indicia 112 adjacent its periphery which is adapted to be exposed before a window 113 formed in the member 87.

The lever 111 is provided with an extension 120 or arm 115 which is provided with a flag or semaphore, as shown at 97, indicating that the side represented by the designation 116 is "vulnerable".

This flag is exposed through the window 113 when the lever 111 has been moved to one end of 125 a slot 117 which is formed by the slits 118 and 119.

The members 86 and 87 are cut out along their edges, as shown at 120, to provide an open space through which the portions of the disc 110 project 130 so that the operator may readily engage the disc and revolve the same when desired.

It will be noted by this construction that either the lever 95 or 111 is adapted to be moved along their respective slots 102 or 117 for placing the 135 flag 97 before the respective windows. The game count is visibly demonstrated or disclosed by revolving either the disc 90 or 110 so that the numerals on the disc will appear before their respective windows.

I claim:

1. In a score pad, a relatively rigid cover member formed of a pair of sheets of material spaced from each other, discs provided with numerals at the peripheries thereof and located between the sheets, means for rotatably mounting the discs, portions of the discs being located in overlapped relation, one of the sheets having cut-out portions forming windows for exposing the numbers as representing the game score for a partnership 150

at various stages during a game of bridge, said windows being in longitudinal alignment, and means adapted to be moved into alignment with a window adjacent an exposed number indicating in a co-operative manner with the number exposed the condition of a partnership.

2. In a score pad, a relatively rigid cover member formed of a pair of sheets of material, one of the sheets having cut-out portions forming windows, a lever pivotally mounted adjacent each window, an arm projecting from the lever and having the free end thereof provided with indicia adapted to be exposed before a window, the last-mentioned sheet having arcuately disposed slots adjacent the lever for exposing a portion of the lever whereby said lever may be operated for moving the free end of an attached arm before a window.

3. In a score pad, a relatively rigid cover member formed of a pair of sheets of material, one of the sheets having cut-out portions forming windows, a lever pivotally mounted adjacent each window, an arm projecting from the lever and having the free end thereof provided with indicia adapted to be exposed before a window, the last-mentioned sheet having a pair of arcuately-shaped and concentrically disposed slits adjacent each lever thereby forming an arcuately-shaped strap, the free end of a lever being located between a proximate strap and the inner face of said sheet, the portion of the lever between a pair of slits being exposed to view and adapted to be engaged by the finger of an operator for oscillating the lever and for moving the free end of the arm before a window.
